To all whom it may concern:

Be it known that I, Walter Dorwin Teague, a citizen of the United States and a resident of Annandale, county of Hunterdon, and State of New Jersey, have invented a new, original, and ornamental Design for a Service Station, of which the following is a specification, reference being had to the accompanying drawings, forming a part hereof:

Fig. 1 is a front perspective view of a service station building showing my new design.

Fig. 2 is a front perspective view taken from the opposite side of the building as shown in Fig. 1; and

Fig. 3 is a side elevation thereof.

The rear of the building is plain in appearance.

I claim:

The ornamental design for a service station, as shown and described.
